UNITED STATES PATENT OFFICE.

SEDGWICK PRATT, OF PASADENA, CALIFORNIA.

PHOTO-EXPOSURE METER.

No. 910,230.

Specification of Letters Patent.

Patented Jan. 19, 1909.

Application filed April 28, 1908. Serial No. 429,697.

To all whom it may concern:

Be it known that I, SEDGWICK PRATT, a citizen of the United States, and a resident of Pasadena, in the county of Los Angeles and State of California, have invented a new and Improved Photo-Exposure Meter, of which the following is a full, clear, and exact description.

My invention relates to instruments for measuring the degree of exposure to light, for instance in photography, my more particular purpose being to provide a photo-exposure meter having quite a number of uses and involving a minimum of mechanical parts.

Reference is to be had to the accompanying drawings forming a part of this specification, in which similar characters of reference indicate corresponding parts in all the figures.

Figure 1 is a plan view of the complete instrument which comprises a metallic box provided with a card resting upon its bottom and provided with graphic symbols, and inclosed within the box and revoluble in relation to the card is a disk of transparent material provided with other symbols having a predetermined relation to those first mentioned; Fig. 2 is a section upon the line 2—2 of Fig. 1, looking in the direction of the arrow and showing the mechanical construction of the box and its contents; Fig. 3 is a plan view of the circular card which rests upon the bottom of the box, this view further showing a number of lines, curves and graphic symbols wherewith the card or stationary member of the device is provided; and Fig. 4 is a plan view of the transparent disk, made preferably of celluloid and mounted within the box, this disk being revoluble relatively to the circular card and being provided with lines, graphic symbols and other indicating members having a predetermined relation to various lines and graphic symbols of the card.

A metallic box 5 is provided with a back 6 and is further provided with an overhanging flange 7, the latter being secured in position by aid of a rim 8 integral with it. Mounted within the box and secured against the back 6 is a circular card 9. A disk 10 of celluloid is mounted revolvably within the box and disposed in loose engagement with the card 9. A disk 11 of glass is secured to the celluloid disk 10 and is provided with a thumb piece 12 whereby both of these mem-

bers, considered as a unit, may be turned relatively to the circular card 9.

Extending diametrically across the celluloid disk 10 is a line 13 having adjacent to its central point the numeral 1. This line, in some of the uses to which the instrument is put, designates the horizon, as hereinafter explained. Disposed upon opposite sides of the line representing the horizon are a number of other lines 14 parallel with each other but spaced at unequal distances from the line 13, as will be understood from Fig. 4. These lines 14 are provided with various numerals from 60 to 800 and between the numeral 60 and the numeral 1 of the line 13 is the numeral 30. The numerals 30 to 800 are duplicated; that is, they extend in two directions from the center, as will be understood from Fig. 4. The numbers 1 to 800 represent what I designate as a "diaphragm-time scale."

The celluloid disk is further provided with a pointer 15 having preferably the form of an arrow, as shown in Fig. 4, this pointer being immovable relatively to the celluloid disk. The circular card 9 is provided with a circle 16 and disposed adjacent to a portion of the latter are graduations 17 arranged in a row of substantially arcuate form, as will be understood from the upper portion of Fig. 3. Disposed adjacent to these graduations are numerals 0 to 90 inclusive, constituting what I designate as a "latitude scale."

Immediately inside of the circle 16 and disposed adjacent to the latitude scale just mentioned, are numerals 1 to 800, indicating, as in the disk 10, a diaphragm-time scale. The circular card 9 is provided with a number of lines 18 parallel with each other but spaced apart by unequal distances. I designate these lines as "date lines." Crossing their general direction and disposed close to their ends are various dates ranging from June 21 to December 21, and from December 21 to June 21, these dates being arranged in columns 19, 20, which, for convenience, I designate as "date columns."

A number of lines 21, some curved more than others, are placed upon opposite sides of a central line 22 and spaced at unequal distances therefrom. The lines 21, 22 represent hours and are provided at their upper ends, and also at their lower ends, with numerals representing hours. While these numerals run only from 1 to 11, it will be un-

derstood that a portion of the circle 16 represents the 12th.

The upper portion of the circular card 9 is provided with the following legend: 5 "Afternoon hours Southern Hemisphere, morning hours Northern Hemisphere." For convenience in Fig. 3 this legend is designated as 23. The lower portion of the card is somewhat similarly provided with the 10 legend "Afternoon hours Northern Hemisphere, morning hours Southern Hemisphere." This legend is designated as 24.

The numerals 1 to 800 appearing in the diaphragm scales upon the celluloid disk 10 and upon the circular card 9 are determined by ascertaining the product of the so-called "stop number" used in the camera to be employed, and multiplying the same by the reciprocal of the corresponding time of exposure for normal conditions and for the particular latitude and time of day. For abnormal conditions some allowance should be made by multiplying a proper factor. The so-called "stop number" to be employed 20 in making an exposure, divided by the reading of the diaphragm-time scale, as herein-after pointed out (or as corrected for abnormal conditions) will be the required time of exposure in seconds. 25

30 The construction of the date lines 18 and of the other lines spaced equidistant and used upon either the circular card 9 or the celluloid disk 10, are determined mathematically. These being mere details to be 35 employed in practical construction, I do not deem it necessary to describe them.

The uses to which my invention can be placed are many and varied. For the sake of simplicity, I herein describe only a few 40 of them. In describing the use of the instrument, the stop numbers referred to will be understood as the ordinary stop numbers relied upon in the use of cameras and as having a conventional designation given them 45 by photographers in actual practice.

The particular use of the diaphragm-time scales may be best understood by a particular example. Suppose it be desired that we 50 find the time of exposure when the latitude is not known and also when the time of day is not known. This may be done by turning the disk 10 until the line 13 (representing the horizon) reaches the 90° mark of the latitude scale (upper left hand in Fig. 55 3). The operator now holds the instrument in his left hand at the height of the eye, maintaining the line 13 vertical. The sun is now to the right and just shining upon the face of the instrument. If a straight 60 edge, such as a pin or a match, be now moved along perpendicular to the right side of the instrument until the shadow of the straight edge passes exactly through the center of the instrument, the operator may read 65 the diaphragm-time scale (indicated by the

numbers 1 to 800), and taking the approximate number where the shadow cuts this scale and dividing the stop number by this number, the time of exposure is ascertained.

The operation of my device is as follows: 70 Suppose the operator is in latitude 40° north, that the date is August 21, the time of day 9 a. m., and that the normal conditions obtain. Suppose further, that the particular stop to be used is the one designated 75 ordinarily as "No. 10, U. S." The question is, what should be the time of exposure for the conditions just stated? In order to solve this question the operator moves the thumb piece 12, and consequently turns the celluloid 80 disk 10 and glass plate 11 (these two members acting as a unit) so that the arrow 15 points to the numeral 40 in the latitude scale in the upper portion of the card 9, as will be understood from Fig. 1. Selecting from 85 the date column 19 the date in question, to wit, August 21, the operator follows the date line associated with this date, and finds where this line meets the particular hour curve corresponding to 9 a. m. of the Northern Hemisphere. From the point constituting the junction of these two lines he now ascertains the nearest of the parallel lines 13, 14 upon the celluloid disk, and having done this he follows the particular line 90 until it reaches the diaphragm-time scale (indicated by numerals 1 to 800), and reads the nearest number of the scale. This he finds to be 380. Now, dividing the stop number 10 by the reading thus ascertained, 100 he has 10 divided by 380, which gives $\frac{1}{38}$. The required time of exposure is therefore $\frac{1}{38}$ of a second. Suppose, however, that the conditions laid down are not quite the same as those just described, there being a 105 variation in the fact that instead of a normal landscape the subject to be photographed is a portrait which is located in the shade of a building without any overhead cover. In this case we should find, as above, 110 the diaphragm-time reading, namely, 380, and multiply by a modifying factor, say $\frac{1}{2}$, this being an arbitrary allowance, supposedly sufficient to cover the difference in the degree of light thrown upon the portrait, 115 and that which should be thrown upon a normal landscape. This gives 380 multiplied by $\frac{1}{2}$, equal to 76, and dividing the stop number 10 by 76 we have $\frac{1}{76}$ of a second nearly, as the time required for exposure. 120

Examples analogous to the two just stated arise quite frequently in practice. There are also a number of other examples which I state for the sake of clearness, as follows:

Example 3: Latitude 34° north; date, 125 November 6; time of day, 10.30 a. m.; stop number 4 U. S.; sun dimmed by light clouds; Hammerslow plate to be used. What would be the time of exposure?

Solution: Set the instrument so that the 130

pointer 15 designates latitude 34; look in the date column 19 for November 6. No such date is given but we find November 1 and November 11. We know that in fact November 6 is about half way between November 1 and November 11, and we therefore imagine the date line to be drawn between the lines referring to November 1 and November 11. We follow the imaginary line 10 until it meets the hour curve designating the time of day, to wit, 10.30, which, if drawn, would meet a parallel line half way between the parallel lines designated as 250 and 380. We now find that the diaphragm-time reading is 250 plus 380, all divided by 2 equaling 315. Multiplying this by $\frac{2}{3}$ so as to allow for the fact of the sun being dimmed by clouds, and by 0.3 for the use of the Hammerslow plate, we have 315 multiplied by $\frac{2}{3}$ multiplied by 0.3, equals 38 nearly, and dividing 4 by this number we have $\frac{1}{10}$ nearly, as the fraction of a second of exposure required.

Example 4: Date, June 21; latitude 40° north. What is the mean time (approximately) of sunrise and sunset?

Solution: Set the meter so that the hand 15 points to number 40 in the latitude scale, meaning 40°. Follow the date line of June 30 21 to a point where it intersects the parallel line through the center of the meter. This parallel line, as above explained, represents the horizon. The hour curve at the intersection of the two lines would be 4.35 a. m. 35 This would represent the time of sunrise. The other end of the hour curve would represent 7.25 p. m. or sunset.

Example 5: At what latitude is the sun overhead at noon on June 21, in the Northern Hemisphere?

Solution: Turn the disk 10 until the parallel 800 is tangent to the circle 16 at the point indicating June 21. Now read the latitude as indicated by the arrow; the answer will be found to be 23 $\frac{1}{2}$ °. In this connection it may be noted that the parallel lines form practically a scale of altitudes of the sun and are 10° apart, the zero of the scale being, of course, the line 13 representing the horizon and extending directly across the center of the disk.

Example 6: At 66° north latitude, what is the altitude of the sun at noon on December 21?

55 Solution: Set the disk 10 to 66° latitude. The line 13, representing the horizon, now passes through the designation December 21 at the point representing noon. The answer, therefore, is 0°.

60 Example 7: At 30° south latitude, what is the altitude of the sun at 9 a. m. March 11?

Solution: Set the disk to 30° latitude. Follow the March 11 date line to the 9 65 a. m. hour course (Southern Hemisphere)

where the parallel 380 will be found to pass. In the latitude scale (which relatively to the diaphragm-time scale below it is an altitude scale) 40° corresponds to 380. The altitude is therefore 40°.

Example 8: Where and when are sunrise and sunset at the same time?

Solution: The instrument shows this will be the case everywhere on March 21 and September 21, and always at 0° latitude.

Example 9: At what latitude in the Northern Hemisphere will the time of exposure be the same at any time of day during the 24 hours the same date, under the same conditions? Answer: 90°. During what months is this true? Answer: From March 21 to September 21. And on July 21, using stop number 10 U. S., normal conditions, what should be the exposure? Answer: $\frac{1}{150}$ or $\frac{1}{15}$ of a second. At the equator on this date, this exposure should be given at 7.25 a. m. and at 4.35 p. m.

The following directions may be conveniently placed upon the back of the box if desired: Turn glass till arrow points to the 90 latitude; follow date line till it meets the hour curve, and from this point follow red line or parallel thereto (in Northern Hemisphere, and black line in Southern Hemisphere) till scale on glass is met. The 95 stop number (uniform system) to be used divided by the scale reading will give the time of exposure for normal conditions.

Normal conditions. Open landscape; open foreground; no dark objects near camera; 100 clear sky; N. C. films. For other conditions multiply scale reading as follows: Average landscape, light foreground, small dark objects in foreground; buildings 30 to 50 feet away; foliage, figures, etc., at mid-distance: 105 Multiply by $\frac{1}{2}$ or 0.5. Dark objects or portraits out doors in shade, no overhead cover: Multiply by $\frac{1}{3}$ or 0.2. Same and overhead cover, multiply by $\frac{1}{10}$ or 0.1. Snow view; mid-sea view; heavy clouds; far-distant 110 landscape: Multiply by $1\frac{1}{2}$ or 1.25. Distant sea view, light clouds, multiply by $3\frac{1}{2}$ or 3.5. Sun dimmed by light clouds or haze: multiply by $\frac{2}{3}$ to $\frac{1}{2}$. Seed's 27 and similar plates, multiply by $\frac{1}{10}$ or 1.1. Seed's 26 X, etc., 115 multiply by $\frac{7}{10}$ or 0.7. Seed's 23, etc., multiply by $\frac{3}{10}$ or 0.3.

Having thus described my invention, I claim as new and desire to secure by Letters 120 Patent:

1. The combination of a card provided with lines, a disk of transparent material mounted upon said card and revoluble in relation thereto; said disk being provided with lines adapted to be brought into registry with said lines upon said card, said disk being further provided with numerals for designating the lines upon it, and being further provided with a character serving 125

as a pointer and adapted to be brought into registry with predetermined portions of said card and a box for receiving the card and the disk and provided with an overhanging flange for engaging the face of the disk.

2. In a device of the class described, a box comprising a back and a rim, a circular card within the box provided with a latitude scale, and a disk of transparent material mounted upon the card, and rotatable with respect thereto, and provided with lines adapted to be brought into register with

different portions of the latitude scale, the rim of the box being provided with an overhanging flange for retaining the disk and 15. the card in place.

In testimony whereof I have signed my name to this specification in the presence of two subscribing witnesses.

SEDGWICK PRATT.
